UNITED STATES PATENT OFFICE.

CLAUD A. ELLIS, OF ST. CHARLES, ILLINOIS, ASSIGNOR TO THE FAULTLESS IRON WORKS, OF ST. CHARLES, ILLINOIS.

DESIGN FOR A METALLIC STORAGE-CABINET.

44,093.

Specification for Design.

Patented May 27, 1913.

Application filed January 24, 1913. Serial No. 744,029. Term of patent 14 years.

To all whom it may concern:

Be it known that I, CLAUD A. ELLIS, a citizen of the United States, residing at St. Charles, in the county of Kane and State of Illinois, have invented a new, original, and ornamental Design for a Metallic Storage-Cabinet, of which the following is a specification, reference being had to the accompanying drawing, forming part thereof.

The figure is a perspective view of a me-

tallic storage cabinet, showing my new design.

I claim:

The ornamental design for a metallic storage cabinet, as shown.

CLAUD A. ELLIS.
